Fig 1

FIG 2

FIGURE 1 is a front perspective view of a figurine, showing my new design; and

FIGURE 2 is a rear perspective view thereof with a power cord being shown in broken lines for illustrative purposes only.

The dominant features of the design reside in the combination on the design disclosed of the fringed wings fastened at the back of the gown waistline, the double fringed treatment extending from the neckline to the hemline of the gown and the forwardly extending arms having hands fashioned of lightbulbs, all as shown.

I claim:

The ornamental design for a figurine, substantially as shown and described.
